SORTING OF YARN PACKAGES

Albert Fairholme Guyler, Spondon, near Derby,
England, assignor to Celanese Corporation of
America, a corporation of Delaware

Application March 15, 1940, Serial No. 324,046
In Great Britain March 21, 1939

4 Claims. (Cl. 209—87)

This invention relates to the sorting of yarn packages, and particularly with the sorting of yarn packages in accordance with the amount of yarn contained thereon. The invention is especially concerned with incomplete yarn packages and it is an object of the invention to provide a method and means for sorting such incomplete packages in accordance with the amount of yarn contained thereon.

According to the present invention yarn packages are sorted in accordance with the amount of yarn contained thereon by allowing them to rest in an opening whose width is controlled by movable elements, e. g. spring-loaded flaps, and pressing open said elements to a predetermined extent, whereby packages below a certain diameter, depending on the extent of pressing, pass through the opening, while packages above that diameter do not. Conveniently, the opening may be pressed by stages to successively greater widths until the package finally passes through the opening at a stage depending on the amount of yarn thereon.

An apparatus according to the invention for carrying out the process outlined above comprises a member having an opening therein, movable elements mounted in said opening to control the width thereof, means for pressing said elements to a predetermined extent and means for collecting the packages passing through said opening. Conveniently, a member may be provided having a plurality of openings therein and a plurality of means for widening said openings to different predetermined extents may be provided, the member in which the openings are formed being moved so that each of said openings in turn passes successively under the influence of each of said widening means. Thus, the member containing the openings may be in the form of a rotating table and relatively simple means such as fixed cams relatively to which the table rotates may be provided for successively widening the openings.

The invention is particularly applicable to the sorting of bobbins or similar packages that are to be employed for the making of warps. The invention is especially convenient where the packages contain artificial yarns and more particularly artificial yarns produced by the dry spinning or evaporative method that is frequently employed in the production of yarns of cellulose acetate or other organic derivative of cellulose. In the production of artificial yarns the yarns may be wound as they are produced upon bobbins or like packages for which purpose a

5 machine may be employed on which a large number of bobbins are wound simultaneously. It is convenient to run the bobbins for a predetermined time so that a predetermined amount of 10 yarn is wound thereon, the bobbins on a given machine being systematically changed when they are full so that they all run for the same time. Where a breakdown occurs, however, so that one or more bobbins on the machine have not been 15 running for the full predetermined time, it is not convenient to leave such bobbins after the rest have been changed and consequently some bobbins may be produced which do not carry the full quantity of yarn. When such bobbins are 20 employed for warping they do not run for the same number of warps as the other bobbins which contain the full quantity of yarn and this leads to inconvenience and delay in the warping operation. Consequently it is desirable that these 25 bobbins should be segregated from the rest and used separately, and further that they should be sorted whereby in a single warping operation there may be employed a number of incomplete bobbins all containing substantially the same quantity of yarn. The present invention is, therefore, useful for sorting out the incomplete bobbins for this purpose.

In the machine according to the invention 30 spring-loaded elements may be provided for controlling the width of the openings in which the packages rest. These elements may be in the form of a pair of flaps hinged at opposite edges of a rectangular hole and spring-loaded so that their edges are normally a sufficient distance apart just to allow an empty package to pass between them. Where the packages to be 35 sorted are flanged bobbins the flaps may be made so that their hinged sides do not occupy the whole side of the rectangle to which they are attached but leave a space at each end for the accommodation of the bobbin flange. The springs by 40 which the flaps are loaded should be sufficiently strong to support the weight of a full package placed in the opening, cams or other pressing means being relied on to force the flaps against the action of the springs so that the flaps open until the package falls through.

Feeding of the bobbins or other packages to 45 the holes into which they are to be pressed may be effected by any convenient means, preferably of an automatic nature. Thus, they may be passed down a chute or run-way to be released at the bottom as each hole passes the lower end of the chute or run-way. Where a table containing a number of holes is employed there may be

a single feeding device at one point of its periphery or there may be two or more feeding devices at different points, with a series of cams extending from each feeding point to the next. In the latter case only one of the feeding devices may be left in action when it is desired to increase the number of classes into which the bobbins are sorted, the cams being readjusted as a single series of steadily increasing depth.

By way of example, one form of the apparatus will now be described in greater detail with reference to the accompanying drawings, in which—

Figure 1 is a diagrammatic plan view of the apparatus as a whole;

Figure 2 is an enlarged plan view of part of the apparatus, broken away to show certain details;

Figure 3 is a radial section of one side of the apparatus; and

Figures 4, 5 and 6 show various details of the apparatus.

The apparatus is adapted for the sorting of flanged bobbins of about $4\frac{1}{2}$ inches in length and $2\frac{1}{2}$ inches in flange diameter. The apparatus comprises a circular table 1 having round its edge twelve rectangular holes 2 a little over $4\frac{1}{2}$ inches by $2\frac{1}{2}$ inches, the longer axis being disposed radially with respect to the table. Hinged to the substantially radial sides of each hole are a pair of flaps 3 about 3 inches in length and $\frac{3}{8}$ of an inch in width. The table is rotatably carried on a central plate 4 and is driven by means of a friction wheel 5. Instead of a friction wheel 5, a pinion may be employed, engaging with gear teeth round the periphery of the table, but in this case it is preferable to include in the drive to the pinion a friction clutch which may slip in the event of a bobbin jamming in the machine.

Bobbins indicated at 6 are fed to the holes 2 successively as they pass a feeding station at a point on the periphery of the table, i. e. the point shown at the top of Figure 1. The bobbins, when sorted, emerge from beneath the table along chutes indicated at 7, two bobbins 8 and 9 of different sizes being indicated in Figure 1 as emerging from two chutes at different points around the periphery of the table.

As is shown in Figures 2 and 3, each of the flaps 3 is mounted on a horizontal spindle 10 in bearings 11 on the underside of the table 1, and the spindles 10 are provided at their inner ends with toothed segments 12, 13, which interengage so as to ensure that the two flaps 3 in each opening occupy corresponding angular positions. The flaps 3 are spring-loaded by means of a spring 14 secured at one end to the segment 12, and at the other end to an upstanding flange 15 forming part of the table 1. A stop 16 is provided to limit the motion of the segment 12, so that the flaps 3 occupy a limiting position below the plane of the table 1. The spindle 10 carrying the other segment 13 is provided also with an arm 17 having at its other end a cam follower 18 which engages successively with a series of twenty-four cams 19, carried beneath the central plate 4 of the machine. Each of the cams 19 is guided by a guide rod 22 extending downwardly beneath the plate 4 and its height is controlled by means of a screw 23 operated by a notched head 24, any accidental motion of which is prevented by means of springs 25 secured at 26 to the central plate 4 and fitting into the notches 27 in the head 24. By these means the cams 19 may be adjusted to any desired height, and they are adjusted as shown in Figure 6 so as to push the cam

follower 18 successively downwards as the table 1 rotates.

In Figure 6, the five adjacent cams shown cover, for illustrative purposes, the whole range from empty bobbins to full bobbins, but it will be understood that in practice the range covered by five adjacent cams will usually be far less, so that the whole range is distributed round the periphery of the machine. A return cam 29 is provided, following the last of the cams 19, and the cam follower 18 rises up the cam 29 as the opening returns to the feeding station.

The central plate 4 is stiffened by means of webs 20 and carried on a central pillar 21 indicated in Figure 1. The table 1 is supported on the central plate 4 by means of a bearing 28 (Figure 3).

Beneath the table 1 are disposed a number of radial chutes 7, one for each of the cams 19, the chutes 7 being adapted to receive the bobbins as they drop through the opening 2, and to direct them to suitable containers disposed outside the periphery of the machine. At the feeding station, to which the bobbins 6 are fed (Figure 1), is disposed a pair of stationary cams 31 indicated in Figure 5, adapted to receive the flanges 32 of the bobbins as they are fed into each opening, so that as the table moves round, the bobbins roll on their flanges gently down the slope 33 of the cam 31, and are deposited gently on the flaps 3 of the opening 2.

In the operation of the machine, the bobbins 6 are fed successively to the openings 2, successively occupying the feeding station, and their flanges are received by the cam 31 disposed beneath the feeding station. As the table rotates, each bobbin is first rolled down the slope 33 of the cam 31 so that its barrel is gently engaged with the edges of the flaps 3. At this stage, the edges of the flaps 3 are at a sufficient distance apart to allow the passage of any bobbin which is empty, or which contains so little yarn as to be useless. If the bobbin, however, contains any greater amount of yarn, the edges of the flaps 3 at the feeding station are close enough to one another to prevent the bobbin passing through. As the table 1 continues to rotate, the cam follower 18 on the lever 17 engages successively with the series of cams 19, and is pressed successively downwards. By these means, the flaps 3 are forced open against the action of the spring 14, so that the distance between the edges of the flaps is increased to successively greater extents. Ultimately, a stage is reached where the flaps 3 are wide enough apart for the bobbin resting between them to slip between them, and at this stage, which depends upon the amount of yarn on the bobbin, the bobbin falls through, is received by a chute 30 and directed to a container. Thus each container receives bobbins carrying a certain amount of yarn, bobbins containing less yarn having been delivered to a previous container, and bobbins containing more yarn being retained and delivered to a subsequent container. In this manner, the bobbins 6 are divided into twenty-four groups, one for each of the cams 19. If a coarse grading is desired two or more feeding stations may be employed, distributed round the periphery of the machine, the bobbins being sorted into as many groups as there are cams between one feeding station and the next.

Having described my invention, what I desire to secure by Letters Patent is:

1. Apparatus for sorting yarn packages in accordance with the amount of yarn contained

thereon, said apparatus comprising a rotatable table having a circular series of openings therein, a pair of spring-loaded flaps for each opening, hinged one on each side of each opening, a plurality of cams, disposed in a circular series corresponding to said series of openings, and each adapted to press said flaps open to a predetermined extent, the cams overlapping each other to provide a continuous operating edge, separate means for adjusting independently the extent of opening produced by each of said pressing cams, and means for collecting packages passing through said openings at each of said pressing cams.

2. Apparatus for sorting yarn packages in accordance with the amount of yarn contained thereon, said apparatus comprising a rotatable table having a circular series of openings therein, a pair of spring-loaded flaps for each opening, hinged one on each side of each opening, a plurality of cams, disposed in a circular series corresponding to said series of openings, and each adapted to press said flaps open to a predetermined extent and each formed so as to give a dwell the cams overlapping each other provide a continuous operating edge of inclines ultimating with dwells, separate means for adjusting independently the extent of opening produced by each of said pressing cams, and means for collecting packages passing through said openings at each of said pressing cams.

3. Apparatus for sorting flanged bobbins in accordance with the amount of yarn contained thereon, said apparatus comprising a rotatable table having a circular series of openings therein, a pair of spring-loaded flaps for each opening, hinged one on each side of each opening, said flaps being shorter, along their hinged sides,

than said openings so as to leave the ends of said openings clear for the passage of the flanges of the bobbins, means for feeding the flanged bobbins to said openings at a fixed point, a cam beneath the openings at said point, said cam being adapted to engage the flanges and to allow the bobbins to come gently into contact with said flaps, a plurality of means, disposed in a circular series corresponding to said series of openings, and each adapted to press said flaps open to a predetermined extent, and means for collecting bobbins passing through said openings at each of said pressing means.

4. Apparatus for sorting flanged bobbins in accordance with the amount of yarn contained thereon, said apparatus comprising a rotatable table having a circular series of openings therein, a pair of spring-loaded flaps for each opening, hinged one on each side of each opening, means for gearing said flaps together so that they occupy corresponding angular positions, said flaps being shorter, along their hinged sides, then said openings so as to leave the ends of said openings clear for the passage of the flanges of the bobbins, means for feeding the flanged bobbins to said openings at a fixed point, a cam beneath the openings at said point, said cam being adapted to engage the flanges and to allow the bobbins to come gently into contact with said flaps, a plurality of means, disposed in a circular series corresponding to said series of openings, and each adapted to press said flaps open to a predetermined extent, separate means for adjusting independently the extent of opening produced by each of said pressing means, and means for collecting bobbins passing through said openings at each of said pressing means.

ALBERT FAIRHOLME GUYLER.
